UNITED STATES PATENT OFFICE.

ARTHUR P. MELTON, OF MINNEAPOLIS, MINNESOTA, ASSIGNOR TO MIRACLE PRESSED STONE COMPANY, OF SIOUX FALLS, SOUTH DAKOTA, AND MINNEAPOLIS, MINNESOTA, A CORPORATION OF SOUTH DAKOTA.

SIDEWALK-BLOCK-MOLDING MACHINE.

No. 825,918.

Specification of Letters Patent.

Patented July 17, 1906.

Application filed August 18, 1905. Serial No. 274,672.

To all whom it may concern:

Be it known that I, ARTHUR P. MELTON, a citizen of the United States, residing at Minneapolis, in the county of Hennepin and 5 State of Minnesota, have invented new and useful Improvements in Sidewalk-Block-Molding Machines, of which the following is a specification, reference being had to the accompanying drawings, forming a part thereof.

10 The purpose of this invention is to provide an improved appliance for molding concrete blocks, particularly of the form suitable for sidewalk-building or like purposes requiring blocks having one finished face of large area 15 relatively to the thickness of the block.

It consists of the features of construction set out in the claims.

In the drawings, Figure 1 is a side elevation of a machine embodying this invention, 20 showing the platen-carrier elevated and the molded block thereon ready for removal. Fig. 2 is a top plan view of the same with the platen removed. Fig. 3 is a section at the line 3 3 on Fig. 1. Fig. 4 is a section at the line 4 4 on Fig. 2. Fig. 5 is a detail section at the line 5 5 on Fig. 4. Fig. 6 is a detail section at the line 6 6 on Fig. 3.

This machine comprises a stand consisting of two side standards 1 1, each comprising 30 two legs and connecting-webs 2 and 3, the former at the top and the latter nearer the bottom than the top. The two standards are connected by the X-shaped cross-frame 4, having its four terminals bolted two 35 against each of the standards at the lower cross-web 3 of the latter. The standards are further connected by the top 5, which is a rectangular frame, said standards having suitable horizontal webs 1^c at the top in the 40 angle between the two flanges constituting the respective legs for bolts which take through said webs 1^c and corresponding webs 5^c in the angles between the vertical webs of said top frame at the four corners. 45 The top frame 5 has in addition to its four sides a cross-web 6, which is T-shaped in cross-section and which connects two opposite parallel sides of the frame midway between the other two opposite sides. This 50 cross-web is depressed at the middle point of its length and has at that point a boss 6^a,

vertically-apertured to afford guide-bearing for a thrust-rod, hereinafter described, for lifting the platen. The opening, generally rectangular, in this top frame besides being 55 interrupted by the cross-web 6 is further interrupted by four lugs 5^b, forming platen-rests, which project two from each of the two opposite sides of the frame, which are connected by the cross-web 6 about midway between said cross-web and the other two parallel sides of the top frame, leaving the aperture of said latter frame uninterrupted at the four corners. Above the top frame 5 there is mounted an H-shaped spider or platen-lifting frame 7, whose cross-bar 7^a extends crosswise of the cross-web 6 and has at the middle point of its length a boss 7^b, which is adapted to lodge directly above the boss 6^a on a cross-web 6 and from which at its lower 60 side a spindle or stem extends through the aperture of the boss 6^a, which thus becomes a vertical guide-bearing for said stem, which is also otherwise guided, as hereinafter mentioned, to hold the H-shaped platen-lifter 65 7^c horizontal in lifting the platen. The two side bars 7^c of the H-shaped platen-lifter 7 extend alongside the side bars of the frame 5, which are parallel with the cross-bars 6, and thus occupy at their four ends the four corners, respectively, of the generally rectangular aperture of the frame 5, the ends of said side bars 7^c standing thus respectively alongside the four lugs 5^b of the top frame 5, while 70 said lugs or platen-rests project inward with 75 in the margin of the outermost supporting points of the lifter. Upon the upper surface of said side bars 7^c at their upper ends are formed slightly-upraised bosses 7^d, the upper surfaces of which are substantially in the 80 plane of the upper surfaces of the lugs 5^b of the top 5 when the boss 7^a of the H-shaped frame rests upon the upper side of the cross-bar 6 at the central depressed point of the latter above the apertured boss 6^a. Mounted 85 upon the upper side of the top frame 5 is the mold 9, which is a four-sided rectangular frame open directly through from top to bottom, its purpose being to form the side walls of the cavity in which the concrete block is to 90 be molded. For securing it on the top of the top frame it has exteriorly-projecting lugs 9^a, 95 100

and to adapt said top frame to support molds of different dimensions said top has at two opposite sides horizontally-projecting lugs 5^a, having a plurality of bolt-holes 5^b, adapted to correspond in position and register with the bolt-holes which may be formed through the lugs 9^a of molds of different sizes.

8 is a platen, which may be of wood and of which a multiplicity will be employed in operating the machine, one to be used with each block molded and remain with the block, supporting it while it is being cured and hardened. This platen is adapted to be rested upon the upper side of the platen-lifter or H-shaped frame 7, obtaining support not only upon the four slightly-upraised lugs of the latter, but also upon the lugs 5^b of the frame 5. The platens will of course be made of varying dimensions corresponding to the varying sizes of the molds, so as to form a complete bottom for the latter, obtaining support at their end portions which extend beyond the opposite parallel sides of the top frame by lodgment upon the lugs 5^a and which are 20 raised so as to be level with the surface of the upraised lugs 7^a of the H-shaped platen-lifter 7.

For operating the platen-lifter its stem or spindle 10 obtains guide-bearing by extending through the central boss 4^a of the X-shaped cross-frame 4 and also, as above mentioned, through the central boss 6^a of the top frame. At its lower end said stem projects below the cross-frame 4 and is pivotally connected to a pedal-lever 11, which is pivotally connected by a link 12 with one arm of the X-shaped cross-frame 4, said arm having a boss 4^b and a lug 4^c projecting alongside the boss and the link 12 being entered between the boss and the lug and there secured by a pivot-bolt.

13 is a pedal-piece mounted upon the swinging end of the pedal-lever 11, which, it will be noticed, extends in a plane approximately parallel to one of the diagonal arms of the X-shaped cross-frames 4 and emerges past one of the lugs of one of the standards at one corner of the machine, so that it can be reached conveniently for operating the 45 thrust-rod without being in the way of an operator standing, as is most convenient for the purpose of the work, at either side of the machine, and thus making it possible for two or even four operators to assist in the process of filling and tamping the mold, one standing at each of the four sides, either of the two standing at the sides between which the pedal emerges at the corner, being in convenient position for operating the pedal when it is desired to lift the block from the mold.

The form of the platen-lifter as having two side bars and a connecting cross-bar, leaving the other two sides open and rendering it H-shaped, is designed to facilitate the lifting of

the platen from the lifter after it is elevated 65 out of the mold, the entire extent of the two opposite side edges of the platen being accessible at the under side except only at the points where the two terminal bosses 7^a are supported.

70 By the construction of the platen-lifter and the top of the frame into which the platen recedes provision is made for easily clearing the parts of the machine from any droppings from the mold-box or any material which 75 may accumulate under the platen. In this way the platen is adapted to seat itself firmly and squarely on the frame, and by providing the inwardly-projecting lugs or platen-rests 80 at the points illustrated and hereinabove described a large number of supporting-points are provided and distributed about equally around the top of the frame, it being understood that a firm support for the platen is necessary to withstand the tamping of the 85 concrete in the mold, and prevent straining any working or movable parts of the machine.

I claim—

1. In a machine for the purpose stated, in 90 combination with the mold and the stand, which supports it; a platen adapted to form a false or movable bottom for the mold, and a platen-lifter movable to carry the platen up through the mold-space, such lifter being an 95 H-shaped frame or spider.

2. A machine for the purpose stated comprising a rigid stand having an apertured top; an open-bottomed mold mounted on the stand encompassing the apertures thereof; a 100 platen-lifter having a rigid stem for guiding and operating it vertically, and horizontally, extended platen-supporting arms constituting a skeleton support for the platen, the platen carried on said skeleton support adapted 105 to form a bottom for the mold-cavity, the apertured top of the stand having its apertures corresponding to the arms of said skeleton platen-support to permit the latter to pass through the former and being adapted 110 to afford lodgment for the platen at the depressed position to which it is lowered by the lifter.

3. A machine for the purpose stated comprising a rigid stand having an apertured top; 115 an open-bottomed mold mounted on the top, encompassing the apertured portion thereof; a platen-lifter and means for moving it vertically through the mold; said lifter comprising horizontally-extended arms forming a 120 skeleton support for the platen, said arms being in position corresponding to the apertures of said apertured top so that they pass through said top when the lifter is depressed, the form of said apertures and skeleton being 125 such as to afford projections from the margin of the apertures in the top extending inward between the horizontally-projecting arms of

the platen-lifter, whereby the platen is supported at its margins on the stand-top when at depressed position forming the bottom of the mold.

- 5 4. In a machine for the purpose stated, in combination with the mold and the stand which supports it; a platen adapted to form a false or movable bottom for the mold; a platen-lifter and means for moving it vertically through the mold, said platen-lifter having horizontally-extended arms forming an H-shaped skeleton platen-support, the stand-

top being apertured to permit said H-shaped lifter to pass down through the stand for lodging the platen on the top of the latter. 15

In testimony whereof I have hereunto set my hand, in the presence of two witnesses, at Minneapolis, Minnesota, this 7th day of August, 1905.

ARTHUR P. MELTON.

In presence of—

O. W. MIRACLE,
RAY TRAUTMAN.
